UNITED STATES PATENT OFFICE.

LOUIS K. JOHNSON, OF NEW YORK, N. Y., ASSIGNOR, BY MESNE ASSIGNMENT, TO EDWARD N. DICKERSON, TRUSTEE.

TYPE-DISTRIBUTING MACHINE.

SPECIFICATION forming part of Letters Patent No. 244,721, dated July 19, 1881.

Application filed May 28, 1881. (Model.)

To all whom it may concern:

Be it known that I, LOUIS K. JOHNSON, of the city, county, and State of New York, have invented a new and useful Improvement in Type-Distributing Machines, of which the following is a full, true, and exact description, reference being had to the accompanying drawings.

My apparatus is an improvement on the 10 type-distributing machine invented by Chas. W. Dickinson, and relates to an improvement in apparatus for withdrawing the type from the carriers of the same.

The object of my invention is to reduce the 15 depth of the nicks of the type, whereby they are automatically selected, and thereby leave them stronger, and also to increase the bearing-surface which supports the drop-hook which withdraws the type from the carriers.

20 My invention can be clearly understood from the accompanying drawings, in which similar letters refer to similar parts.

Figure 1 represents the perspective elevation of my improvement, showing the hook 25 elevated and resting upon its rest-lever U. Fig. 2 represents a side elevation of the same, showing the rest-lever thrown back and the hook dropped.

The type T are presented by carriers A moving in the channel B to the action of the feelers M M which are part of the reciprocating slide G, known as a "feeler-slide." Motion is imparted to this slide by means of a vibrating cross-bar, H. The slide G is supported and 35 operated on the bed E. Whenever the corresponding type rests in the carrier in front of the feelers M M they will enter the nicks O O in said type, thereby allowing the hook Y to drop, which engages with the ejector D, and 40 removes the type from within the clutch C.

The hook Y is released by means of the pin R, which pin has attached to it the block S. The rest-lever U is pressed forward against the block S by means of a spring, X, one end 45 of which is let into U, and the other rests upon the slide G. This rest-lever U is pivoted at W. Whenever the cross-bar H is thrown forward, thereby moving the slide G by the intervention of the spring K, the nick-pins M

are brought in contact with a type, T, and if 50 they enter the nicks in said type, the pin R is forced back by coming in contact with the type, whereby the rest-lever U is thrown back and its bearing-surface removed from beneath the hook Y, and the hook is allowed to drop. 55 Then the return movement of the bar H withdraws the type by means of the hook Y and ejector D.

The relation between the block S and the rest-lever U is a peculiar one, since the rest-lever U is so connected with the pin R by means of the block S that the initial pressure of R against the type only alters the position of U slightly, but subsequently U is thrown back with a greater velocity than the movement of S. This is due to the fact that when the rest-lever U is thrown forward by means of the spring X it comes in contact only with the upper surface or corner of the block S, while, as R is gradually forced back by the advance 70 of G, the point of contact between the rest-lever U and the block S is changed from the upper to the lower corner of the block S, thereby increasing the relative movement of the rest-lever U, for the reason that the nearer the 75 power is to the fulcrum of a third-order lever the farther will its free extremity move for a given movement of the power. Therefore the latter portion of the movement of U will be more rapid than the beginning of its movement, supposing the slide H to move toward the block S with the same velocity throughout its travel.

As this apparatus was originally constructed, and as it is shown in the patents of C. W. 85 Dickinson and Wm. A. Lorenz, Nos. 174,899, 174,900, and 174,915, a very slight dislocation of the surface of the type, against which the pin R comes in contact, would cause the rest-block upon which the hook-lever rests to stop, 90 as the slide H was advancing earlier than it ought to, and, as a consequence, the nicks in the type were required to be made comparatively deep, so as to permit the advance motion of the slide H without necessarily throwing the hook Y off of the rest-block. This difficulty resulted from the fact that the rest-block stood still so soon as the pin came in 95

contact with the type, and the extent of contact between the under side of the hook and the top of the rest-block was limited by the depth of the nicks.

5 The object of this improvement is to cause the rest-block to move backward when the pin coming in contact with the type is at rest, thereby permitting a large surface of contact between the under side of the hook and the top 10 of the rest-block, so that a less amount of motion of the slide H, and consequently a less depth of nicks in the type, will be necessary.

In the accompanying drawings, if the pin R came in contact with the rest-lever U by 15 means of a narrow horizontal edge formed on the edge of the pin R, the relative backward movement of the top of the rest-lever, as compared with the forward movement of its center W, would be determined by the position at 20 which that thin edge made contact with the advancing face of the rest-lever. If, however, the pin R is provided with the block S, reaching over a considerable vertical distance of the rest-lever U, then the top of that lever will 25 recede, in respect relatively to the advance of its bottom, in a variable ratio, beginning slowly and increasing to a more rapid movement. As arranged, the first part of the retrograde motion is slow, and this is done for the purpose, 30 among other things, of reducing the effect of the blow of the pin R upon the type. When the feelers M M enter the nicks O O the bottom of the block S will be in contact with the rest-lever near its pivot, and then the forward 35 movement of the slide H will impart to the top of the rest-lever its maximum retrograde movement, and a very shallow nick will be sufficient to make certain the action of the hook Y, while the arrangement secures a large supporting 40 and wearing surface between the top of the rest-lever U and the bottom of the hook Y, which it supports.

The blow of the pin R against the type at 45 the instant of impact is reduced to a minimum, because the leverage is then the greatest over the resistance of the spring, and a maximum pressure of the spring only occurs after contact has been made, and it is, in consequence, not so liable to injury.

50 What I claim as my invention, and desire to secure by Letters Patent, is—

1. In combination with a type-withdrawing mechanism, substantially as described, the stationary nick-pins M and movable pin R and 55 movable rest-lever U, whereby the rest-lever U is moved, on the entrance of the nick-pins,

into the nicks of the type by means of a movable pin, R, substantially as described.

2. The rest-lever U, in combination with an ejector-hook, Y, and a movable pin, R, constructed substantially as described, whereby a greater bearing-surface is obtained between the top of the rest-lever and the ejector-hook than would be the case if the pin R and rest-block were one piece. 60

3. The combination of the rest-lever U, pivoted at its bottom, ejector-hook Y, and movable pin R, whereby the top of the rest-lever has a greater motion imparted to it than the nick-pins have in entering the nicks of the type. 70

4. The combination of the fixed nick-pins M, movable pin R, block S, rest-lever U, and ejector-hook Y, combined and connected substantially as described, whereby the entrance of the nick-pins into the nicks of the type gives 75 to the rest-lever U at first a slow movement, which movement is increased by the farther entrance of the nick-pins into the nicks in the type, whereby a large bearing surface between the rest-lever U and the hook Y is obtained, 80 and the hook is prevented from falling by accidental variation of the surface of the type.

5. The combination of the movable pin R, block S, rest-lever U, with its backing-spring X, and ejector-hook Y, substantially as de- 85 scribed.

6. In a type-withdrawing mechanism, the combination of the ejector-hook Y, rest-lever U, movable pin R, block S, and fixed nick-pins M, constructed and combined substantially as described, whereby the impact between the pin R and the type is reduced to its minimum, and the force necessary to operate the rest-lever U is applied gradually on the advance of the nick-pins into the type, not 95 suddenly, at the first moment of impact between the movable pin R and the type. 90

7. In combination with a type-withdrawing mechanism, an ejector-hook supported upon a movable lever having an upper bearing-surface, and combined and connected with apparatus, substantially as described, whereby a slight variation of the surface of the type, owing to accidental foreign substances, will not drop the hook, while a farther advance of the 105 nick-pins into the type will cause the ejector-hooks to drop, thereby withdrawing the type, substantially as described. 100
